UNITED STATES PATENT OFFICE.

OSMER W. SANBORN, OF HEWINS, KANSAS.

SAFETY SNAP-HOOK.

SPECIFICATION forming part of Letters Patent No. 739,226, dated September 15, 1903.

Application filed May 28, 1903. Serial No. 159,185. (No model.)

To all whom it may concern:

Be it known that I, OSMER W. SANBORN, a citizen of the United States, residing at Hewins, in the county of Chautauqua and State 5 of Kansas, have invented new and useful Improvements in Safety Snap-Hooks, of which the following is a specification.

This invention relates to snap-hooks of the safety type for use in connection with harness 10 generally or for other purposes; and the object of the same is to provide an efficient and durable snap-hook which may be easily and quickly operated to engage or release a device adapted to be connected thereto and prevent 15 accidental unshipping of the device or connecting member.

The invention consists in general of a slotted hook having a latch or mousing-piece rotatably disposed therein and a lock element 20 to engage one end of said piece or latch to prevent movement thereof.

The invention further consists in the details of construction and arrangement of the several parts which will be more fully hereinafter described and claimed.

In the drawings, Figure 1 is a perspective view of a snap-hook embodying the features of the invention and shown open. Fig. 2 is a vertical longitudinal section thereof, showing 30 the mousing-piece or latch closed.

Similar numerals of reference are employed to indicate corresponding parts in the views.

The numeral 1 designates the shank of the hook, having a loop or eye 2 at one end for 35 attaching purposes, and at the opposite end a hook 3 of practically circular form projects from the shank and has a slot or bifurcation 4 formed therein, in which a mousing-piece or latch 5, corresponding in curvature to the 40 members of the hook 3, is pivotally mounted for rotating movement, the pivot 6 passing through the mousing-piece or latch 5 at a point near the center thereof.

To limit the opening movement of the 45 mousing-piece or latch 5, the latter is formed with a shoulder 7 to engage the lower reduced end 8 of a catch 9, depressible into the shank and lower portion of the hook 3. The upper terminal of the catch 9 has a flat spring 10 50 extending rearwardly therefrom and secured to the shank 1 adjacent to the eye or loop 2. The spring 10 projects upwardly and operates to restore the catch to normal position. At the point where the forward extremity of the

spring 10 joins the upper end of the catch an 55 angularly-disposed face 11 is formed for allowing a clearance for the terminal of the closing extremity 12 of the mousing-piece or latch 5. When the mousing-piece or latch 5 is closed, the lower end thereof is engaged by 60 the lower reduced terminal 8 of the catch 9, as clearly shown by Fig. 2, and in order to release the mousing-piece or latch it is necessary to depress the spring 10 and catch 9 to clear the extremity 8 from the lower end of 65 said piece or latch. After such clearance or disengagement of the catch from the mousing-piece or latch the latter may be opened, as shown by Fig. 1, and a ring, loop, or other device may be freely inserted in the hook 3. 70 When the mousing-piece or latch is open, the lower portion thereof projects upwardly within the opening of the hook 3, and a pressure on said projecting part of the mousing-piece or latch by the ring, loop, or other device 75 placed in engagement with the hook will cause the mousing-piece or latch to automatically close and become locked.

The improved device will be found exceptionally useful, as well as strong and durable, 80 and it is proposed to ornament the same by plating and also to use such materials in the construction thereof as will be found best adapted for the purpose. Changes in the proportions and dimensions, as well as the 85 minor details of the several parts, may also be resorted to without departing from the spirit of the invention.

Having thus fully described the invention, what is claimed as new is—

1. A snap-hook, comprising a shank with a hooked extremity, a mousing-piece rotatably mounted in said extremity, and a spring-actuated catch arranged to engage both extremities of the mousing-piece. 95

2. A snap-hook, having a shank with a slotted hooked extremity, a mousing-piece rotatably mounted in said extremity and provided with a shoulder, and a spring-actuated catch arranged to engage the extremities of the mousing-piece and also the shoulder of the latter. 100

In testimony whereof I affix my signature in presence of two witnesses.

OSMER W. SANBORN.
